United States Patent Office.

FELIX WALKER, OF NEW ORLEANS, LOUISIANA.

Letters Patent No. 84,031, dated November 10, 1868.

IMPROVEMENT IN SASH-STOP AND HOLDER

The Schedule referred to in these Letters Patent and making part of the same.

To all whom it may concern:

Be it known that I, FELIX WALKER, of the city of New Orleans, parish of Orleans, and State of Louisiana, have invented a new and improved Mode of Securing Sash into Window-Frames, and with an improved device to automatically hold a sash at any height desired, and also to lock both lower and upper sash, by merely elevating or lowering the same.

By the use of my invention, sash will work with more ease, and be more securely and easily fastened than any other mode heretofore used, and will supersede the use of cords and weights to sash, will be cheap and easy of application, and withal very durable; and I do hereby declare that the following is a full and exact description thereof, reference being had to the accompanying drawings, and to the letters marked thereon, similar letters referring to corresponding parts, making a part of this specification, in which—

Figure 1 is a perspective view of a window, and showing a part of my invention.

Figure 2 is a longitudinal section, enlarged to a working-size, of part of a window-frame and sash, showing part of my improvement.

Figure 3 is a transverse section, showing part of a window-frame and two sash, as held by my improvement.

Figure 4 represents my improved "bob," or sash-
catch.

The nature of my improvement consists in providing and attaching, to either side of a window-frame, metallic "stops" or "ways," made of cast or wrought-iron, or of any other suitable material, and to provide, of iron, brass, or any other suitable material, a somewhat v-shaped "bob" or catch, and pivot the same through a slot cut horizontally through the upright frame of a window-sash, the arms of the said "bob" to alternately engage notches on the metallic "ways," attached to the window-frame.

To enable others skilled in the art to make and use my invention, I will proceed to describe its construction and operation.

I make, of cast or wrought-iron, or of any other suitable material, "stops" or "ways," from one to two inches wide, or of any other width desired, and about one-eighth to one-quarter ($\frac{1}{8}$ to $\frac{1}{4}$) of an inch thick, with "flanged" edges, made at right angles with the width of the metallic "stops" or "ways," say, about one-quarter to three-eighths ($\frac{1}{4}$ to $\frac{3}{8}$) of an inch high. On the edges of the flanges, I cut shallow and curved bottom notches. (See A, in fig. 2.) To either side of a window-frame, I attach, with screws s, the metallic "stops" or "ways" A.

On the outer edge of the side or upright part of a sash-frame, I cut, with a suitable tool, grooves to receive and engage the "flanges" on the metallic "stops" or "ways" A, as seen at A and B, fig. 3, the lower sash to engage one of the flanges, and the upper sash the other flange. Thus, both sash to run on the "stop" or "way," as seen at figs. 2 and 3.

I make, of iron, brass, or any other suitable material, a "bob" or catch, with two arms, somewhat v-shaped, and pivoted, one of the arms of the "bob" being so weighted that it can be "tripped," or turned over, so as to perform the two offices, one to hold the sash down, and the other to retain, automatically, the sash at any point desired.

This "bob" or catch, I pivot in a slot cut horizontally through the upright side of a sash-frame, so that one of its arms will constantly engage the notches cut on the flanges of the metallic "stops" or "ways" A, while the other arm of the "bob" or catch will be so exposed or presented that it can be operated on by the hand, when it is desired to move the sash up or down, thus completing the sash-fastener, so as to automatically lock the sash when it is down, and also to stay the same at any point as it is being hoisted, which can be done with the use of only one hand.

The metal "stops" or "ways" A, when attached to the window-frames, are not intended to reach quite to the window-sill, by, say, about one inch, in order to prevent the collection of water, dust, or other substance in the corners of the window.

A represents the metallic "stops" or "ways," with the flanges and notches cut on same.

B represents part of the window-sash.

C represents the metallic "bob" or catch.

S represents the screws attaching the metal "stops" or "ways" to the window-frame.

f represents the flanges on the metal "stops" or "ways" A.

n represents notches cut on the flanges.

p represents pivots passing through the sash and metallic "bob" or catch C.

What I claim as my invention, and desire to secure by Letters Patent, is—

The combination of the double-flanged plate A, with notches n n, and secured to the inner side of the window-frame, with the pivoted catch C, having two arms, one being weighted, as shown, all operating as set forth.

FELIX WALKER.
